UNITED STATES PATENT OFFICE.

DANIEL C. GIDLEY, OF ALBANY, NEW YORK, ASSIGNOR TO CROUSE-HINDS COMPANY,
OF SYRACUSE, NEW YORK, A CORPORATION OF NEW YORK.

ELECTRIC-CONDUIT FITTING.

1,180,838.

Specification of Letters Patent. Patented Apr. 25, 1916.

Application filed October 6, 1910. Serial No. 585,599.

To all whom it may concern:

Be it known that I, DANIEL C. GIDLEY, of Albany, in the county of Albany and State of New York, have invented a certain 5 new and useful Electric-Conduit Fitting, of which the following is a specification.

My invention has for its object the production of an electric conduit fitting by which the electrical appliance supported 10 thereby can be adjusted axially and easily adapted to different conditions and thicknesses of walls concealing the conduit work:—and it consists in the combinations and constructions hereinafter set forth and 15 claimed.

In describing this invention, reference is had to the accompanying drawing in which like characters designate corresponding parts in all the views.

20 Figure 1 is an elevation, partly broken away, of a preferable embodiment of my invention, the contiguous portions of the wall in which the fitting is embedded being also shown in section. Fig. 2 is a top plan 25 of this fitting, partly broken away, and parts being removed. Figs. 3 and 4 are detail views of the sleeve members thereof, Fig. 4 being partly broken away. Fig. 5 is a sectional view of the detached socket 30 member.

1 is the hollow body of my fitting, said body being usually formed of cast metal and having one or more passages for the inlet and outlet of electric wires. The body 35 1 is here shown as cylindrical in top plan and having a flat bottom 2 and an opening 3 in its wall opposite the bottom, and also one or more internally threaded nipples 4 adapted to be connected to the conduits 40 which inclose the electric wires.

The opening 3 is closed by a cap comprising inner and outer telescoping sleeve members 5, 6, one being fixed to the body 1 and the other being adjustable axially of 45 the fixed member. In this embodiment of my invention, the outer sleeve member is fixed and the inner member adjustable, and the outer member is provided with an external annular flange 7 which rests upon 50 the margin 8 of the wall of the body around the opening 3, and is secured thereto by screws 9 extending through said flange and into lugs 10 provided on said margin 8.

Usually, the outer edge of the margin 8 55 is formed with an inwardly extending lip 11

which engages the inner face of the flange 7, and the flange 7 is formed with a lip 12 at its outer edge which engages the outer face of the margin 8. This mode of connecting the body and the outer sleeve member forms a tight joint, and dispenses with the necessity of machine finishing flat surfaces of the flange 7 and wall 8.

The adjustable inner sleeve member 6 is held in its adjusted position by clamping 65 means, as screws 13, extending through spiral slots 14 formed in the outer sleeve member, the screws 13 threading into the inner sleeve member. Obviously, by loosening the screws 13 and turning the inner 70 sleeve member, the screws will pass along the slots from high to low points thereof, or vice versa, and thus arrange the inner sleeve member either farther into or out of the outer sleeve member. The outer sleeve 75 member 5 may be provided with but one of these slots, but in order to more firmly support the inner sleeve member 6, the outer member 5 is usually provided with three of such slots. The inner sleeve member 6 80 is also provided with an inturned flange 15 at its outer end for a purpose to be presently explained.

16 is a socket for an electrical appliance, as a lamp, said socket extending into the 85 inner sleeve member 6 and having terminals 17, 18 at its inner end for connection with the wires within the body. The socket is also provided with the usual central and sleeve terminals which engage the terminals 90 of the electrical appliance.

The cap is constructed to receive sockets of standard makes and sizes and all of such sockets usually are provided at their outer ends with exterior annular flanges, as the 95 flange 19, which laps upon the inturned flange 15 of the inner sleeve member 6 and is secured thereto by screws 20. The periphery of this flange is of less diameter than the interior of the outer sleeve member 5 so that it may, if necessary extend 100 partly within said outer sleeve member.

In some instances, especially in concrete buildings, the conduits and fittings are embedded in the walls, as illustrated in Fig. 1, 105 and the distances vary at which the conduits and the bodies of the fittings are located below the surface of the walls, and in use, by adjusting the inner sleeve member axially, the flange 19 of the socket 16 can be 110

arranged close to the plane of the outer face of the wall or ceiling in which the conduit work is embedded so that the electrical appliance presents a neat and pleasing appearance.

If the wall is being plastered, the position of the sleeve 6 is determined as the plaster is spread toward the sleeve 5 and the screw 13 is set before the plaster is applied around said sleeve.

In concrete walls, the sleeve 6 is adjusted to come flush with, or in proper relation to, the shorings which confine the concrete until it hardens.

15 Although my invention is particularly applicable for use in connection with concealed conduit work, obviously conditions may arise in which it may be used advantageously in exposed or other forms of work.

20 What I claim is—

1. In an electrical appliance, the combination with a hollow body having an opening in one side thereof and a bearing surface on the outer face of the margin of the wall around said opening, the extreme edge of said margin being turned outwardly forming a lip, a sleeve arranged coaxially with said opening and provided with a base flange overlying said margin and having an

25 overturned edge resting on said bearing surface, the lip on said margin project-

ing toward said flange, means for attaching said flange to the side of the body, and an electrical appliance supported within the sleeve, substantially as and for the purpose 35 described.

2. In an electrical appliance, the combination with a hollow body having an opening in one side thereof and a bearing surface on the outer face of the margin of the 40 wall around said opening, the extreme edge of said margin being turned outwardly forming a lip, a sleeve arranged coaxially with said opening and provided with a base flange overlying said margin and having an 45 overturned edge resting on said bearing surface, the lip on said margin projecting toward said flange, means for attaching said flange to the side of the body, a second sleeve adjustably supported within the 50 former sleeve, and an electrical appliance carried by the second sleeve, substantially as and for the purpose specified.

In testimony whereof, I have hereunto signed my name, in the presence of two 55 attesting witnesses, at Syracuse, in the county of Onondaga and State of New York, this 5th day of October, 1910.

DANIEL C. GIELEY.
